CLAIM

I claim the ornamental design for a centrifugal air/oil separator for drysump systems, as shown and described.

DESCRIPTION

FIG. 1 is a perspective view of a centrifugal air/oil separator for drysump systems, showing my new design in an assembled configuration;

FIG. 2 is an exploded perspective view of a first embodiment thereof;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a bottom plan view of FIG. 1;

FIG. 8 is a top plan view of FIG. 1;

FIG. 9 is an exploded perspective view of a second embodiment thereof; and,

FIG. 10 is an exploded perspective view of a third embodiment thereof.

The three embodiments are understood to vary only with regard to an internal member that is visible only in the exploded view.
